CLAIM

The ornamental design for an oral heating apparatus for gum disease treatment as shown and described.

DESCRIPTION

FIG. 1 is a left side view of the oral heating apparatus for gum disease treatment showing my new design.

FIG. 2 is a front view thereof.

FIG. 3 is a bottom view thereof.

FIG. 4 is a right side view thereof.

FIG. 5 is a rear view thereof.

FIG. 6 is a top view thereof.

FIG. 7 is a front left side top perspective view thereof; and, FIG. 8 is a rear right bottom perspective view thereof.

The broken lines shown in Figures illustrate portions of the oral heating apparatus for gum disease treatment that form no part of the claimed design.

1 Claim, 3 Drawing Sheets
